UNITED STATES PATENT OFFICE.

ROY W. ADAMS, OF NEW BRITAIN, CONNECTICUT.

FIGUREHEAD.

Application filed August 2, 1926. Serial No. 126,660.

The improvements set forth herein relate specifically to the figurehead described in United States Patent Number 1,511,044, issued October 7, 1924, to Roy W. Adams. 5 This certain type of figurehead is a representation of a winged figure and has movable wings.

In the accompanying drawings:

Figures 1, 2, and 3 show top, front and 10 side views respectively of a mechanism that tilts the wings of the figurehead in such a way that the upper and under surfaces of the wings would receive the pressure of a current of air alternately, should the current 15 of air be coming from the direction in which the figurehead is pointing. Receiving the pressure of a current of air on the upper and under surfaces alternately, causes the wings to move up and down, or flap, in imitation 20 of the efforts of a flying creature. Figure 2 shows the front view of the mechanism in position within the hollow body of the figurehead, shown in section, and the front elevation of the wing joints, wing arms and 25 part of the wings.

In Figures 1, 2, and 3, 1 is a plate having a slot 2 and a closed groove 3. 21 is another plate having a slot to match the slot in plate 1. Plates 1 and 21 are held together by screws with spacers 13 between them. 6 is a bar extending through the slots in plates 1 and 21. 4 is a crank, located between plates 1 and 21, connected to bar 6, and having a pin 5 which is slidable in 35 groove 3. 15 is a spring held in position by a clip 18 and two spacers or washers 16 and 17 which are fastened to one of the plates. The ends of spring 15 are curled to form an eye at each end as shown in Figures 1 and 3. 26 is a pin which extends 40 through an arm of crank 4. Pin 26 is so positioned that it may engage the eye in either end of spring 15 causing crank 4 to become operatively connected to either end 45 of spring 15. As crank 4 is driven up and down, by the wing arms acting through bar 6, spring 15 is brought under torsion by the arm of crank 4 acting alternately on its two ends. The action of spring 15 causes the 50 pin 5 to follow around groove 3 as crank 4 is moved up and down. As pin 5 follows around groove 3 crank 4 imparts a turning movement to bar 6. In each end of bar 6 is a slot by which each end is operatively 55 connected through a yoke to one of the wing arms 14. As bar 6 is turned the inclina-

tion of the slots in the ends of bar 6 is changed and this change of inclination is imparted to the wings 8 through the wing arms 14.

The action described herein is identical with the action described in the specification of United States Patent Number 1,511,044, the difference in the mechanisms being: The mechanism herein described has a single 60 crank operating between two plates instead of a single plate with a crank on either side and: The mechanism herein described has a torsion spring acting upon an arm of the crank in place of the tension springs used in 70 the mechanism of Patent Number 1,511,044. The torsion spring makes for a smoother and simpler acting mechanism.

In the accompanying drawings Figures 4 and 5 show a top and front view of a type 75 of wing joint used in the figurehead. In Figures 4 and 5, 19 is a cylinder which operates in a sleeve 20; 14 is a wing support member or wing arm which extends laterally through cylinder 19 and sleeve 20. To 80 one end of 14 is fastened the wing 8, the other end is forked with a pin 9 across the end of the fork forming a yoke. Pin 9 operates in a slot in the end of bar 6 as shown in Figure 3. Sleeve 20 is cut away on either 85 side so as to permit angular motion of the wing arm 14 as cylinder 19, which supports wing arm 14, turns in sleeve 20. Wing arm 14 is free to rotate in cylinder 19. This arrangement of members makes it possible for 90 wing arm 14 to execute an angular movement and to rotate. These two motions of wing arm 14 are necessary to the operation of the device. The "flapping" or up and down motion of the wings requires an angular motion of wing arm 14, and the tilting 95 of the wings requires that wing arm 14 be able to rotate.

Figures 6 and 7 illustrate another type of 100 wing joint. In Figures 6 and 7, wing arm 14 extends through a spherical member or ball 22 which is supported between two members 23 and 24, which in turn are set in the body 12. Members 23 and 24 are so shaped as to form a socket-like support for ball 22 as shown in Figure 7. Wing arm 14 105 may be free to rotate in ball 22, or the two members may be made integral since ball 22 may rotate in its socket. Ball 22 operating in a socket makes it possible for wing arm 14 110 to execute an angular movement as well as rotate.

I claim:

1. A representation of a winged figure having a hollow body, movable wings and support members therefor rotatably mounted in said body, plates located within said body, each of said plates having a slot and either of said plates having a closed groove, a bar extending through said slots and having its ends operatively connected to said support members, a crank connected to said bar, said crank having a pin slidable in said groove, a double acting spring operatively connected to said crank in such a way as to cause said pin to follow around said groove in response to wind pressure upon said wings.

2. In a device of the kind described the combination of a member having a cylindrical shaped cavity, a cylindrical member operating within said cavity, a third member extending laterally through said first two members, free to rotate therein, said first member being cut away on each side to permit said third member to have angular motion, a bar connected to one end of said third member for imparting rotatory motion thereto and receiving lateral motion therefrom, and a representation of a wing of a winged creature mounted on the other end of said third member.

ROY W. ADAMS.
